(57) **CLAIM**

The ornamental design for a mesh roaster, as shown and described.

DESCRIPTION

FIG. 1 is an isometric view of my mesh roaster thereof.

FIG. 2 is an enlarged top view thereof.

FIG. 3 is an enlarged isometric exploded view thereof.

FIG. 4 is an enlarged side view thereof; with the opposing side view being a mirror image thereof.

FIG. 5 is an enlarged cutaway detail view of the upper edge thereof; shown for clarity of illustration.

FIG. 6 is an enlarged cutaway detail view of the lower edge thereof; shown for clarity of illustration; and,

FIG. 7 is an enlarged bottom view thereof.

The broken lines shown in the drawings are for illustrative purposes only and form no part of the claimed design.
